UNITED STATES PATENT OFFICE.

HIRAM H. SMITH, OF BROOKLYN, ASSIGNOR TO THE EMPIRE HYDRO CARBON COMPANY, OF NEW YORK, N. Y.

CONCENTRATOR FOR ARTIFICIAL LIGHTS.

SPECIFICATION forming part of Letters Patent No. 363,010, dated May 17, 1887.

Application filed June 9, 1886. Serial No. 204,028. (No model.)

To all whom it may concern:

Be it known that I, HIRAM H. SMITH, a citizen of the United States, and a resident of the city of Brooklyn, county of Kings, and State of New York, have invented a certain new and useful Improvement in Concentrators for Artificial Lights; and I do hereby declare the following to be a description of said invention in such full, clear, concise, and exact terms as to enable any skillful person to make and use the same, reference being had to the accompanying drawings, wherein like letters of reference indicate corresponding parts throughout the several views.

The chief object of my invention is to make a concentrator for artificial lights of improved construction and increased efficiency for concentration and illumination.

In the drawings, Figure 1 shows a central section of this improved concentrator. Fig. 2 shows a bottom plan of the same; and Fig. 3 shows top and bottom plans and side elevation, respectively lettered *a*, *c*, and *b*, of a removable and adaptable elastic cushion to secure perfect fitting upon the burner.

The concentrator itself consists of a solid glass center, *A*, its upper surface plain or slightly concave and its lower surface convex, with radiating solid glass arms, straight or tapered, as shown, having plain or slightly-concave upper surfaces and plain or convex lower surfaces, in section of triangular shape and joined by their bases to the center, as shown plainly in Fig. 1. This particular construction of the radiating arms presents the most faces, almost facets, practicable to refract and concentrate the light for the best illumination. It is intended to use a reflecting-shade above and about the light, resting upon the arms, as indicated by the dotted lines in Fig. 1.

In the center of the concentrator is an opening, which I prefer to make oblong or square, as shown in plan in Fig. 2, with upward slop-

ing sides, as shown in section in Fig. 1. I provide a corresponding cushion, *D*, inserted 45 nicely in the opening and made with a hole to fit upon the ordinary gas-burner, or one specially adapted to a particular purpose. I prefer to make this cushion of rubber; but any similar material sufficiently elastic will answer.

Fig. 3 shows the details of the construction of the cushion described. The difficulty of fitting the concentrator upon any burner or fixture is thus completely overcome, and no 55 change need be made in the general construction of the concentrator to adapt it to any situation, as whatever change may be necessary can be confined to alteration of the cushion.

What I claim as my invention, and desire to 60 secure by Letters Patent, is—

1. A concentrator for artificial light, consisting of a circular plano-convex lens provided with a central opening to fit over and upon the burner, combined about the circumference 65 with radiating quadrangular prisms triangular in longitudinal section and attached by the upper edges of their bases, all constructed and co-operating substantially as specified.

2. A concentrator for artificial light, consisting of a circular plano-convex lens, combined about the circumference with radiating quadrangular prisms triangular in longitudinal section and attached by the upper edges of their bases, the whole provided with an oblong 70 or square opening in the center with inward sloping sides, in combination with an elastic cushion removably fitted in the central opening and provided with an opening in its center to fit over and upon the burner, in the manner and for the purpose substantially as specified.

HIRAM H. SMITH.
